US00D737362S

(12) **United States Design Patent**
Chang et al.

(10) **Patent No.:** US D737,362 S
(45) **Date of Patent:** ** Aug. 25, 2015

(54) **CAMERA CALIBRATION BOARD**

(71) **Applicant:** **HON HAI PRECISION INDUSTRY CO., LTD.**, New Taipei (TW)

(72) **Inventors:** **Chih-Kuang Chang**, New Taipei (TW);
Xin-Yuan Wu, Shenzhen (CN); **Yi Liu**,
Shenzhen (CN)

(73) **Assignee:** **HON HAI PRECISION INDUSTRY CO., LTD.**, New Taipei (TW)

(**) **Term:** **14 Years**

(21) **Appl. No.:** **29/451,974**

(22) **Filed:** **Apr. 10, 2013**

(30) **Foreign Application Priority Data**

Mar. 5, 2013 (CN) 2013 3 0053427

(57) **CLAIM**

The ornamental design for a camera calibration board, as shown and described.

DESCRIPTION

FIG. 1 is a perspective view of a camera calibration board showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
